UNITED STATES PATENT OFFICE.

HENRY E. MOOMAW, OF SALEM, VIRGINIA.

SHEET-METAL ROOFING-PLATE.

1,021,844.

Specification of Letters Patent.

Patented Apr. 2, 1912.

Application filed October 28, 1911. Serial No. 657,264.

To all whom it may concern:

Be it known that I, HENRY E. MOOMAW, a citizen of the United States of America, and a resident of Salem, county of Roanoke, 5 State of Virginia, have invented certain new and useful Improvements in Sheet-Metal Roofing-Plates, of which the following is a full and clear specification, reference being had to the accompanying drawings, in which—

Figure 1 is a perspective view of portions of a pair of roofing plates constructed and connected in accordance with my invention; Fig. 2 a vertical transverse sectional view 15 showing the manner of interlocking adjacent plates; and Figs. 3 and 4 detail perspective views showing the application of my invention to two different designs of roofing plates.

20 This invention has relation to that type of sheet metal roofing covered by my former Patent No. 884,285, dated Apr. 7, 1908, in which is shown and covered a sheet metal roofing plate having an upstanding ridge 25 parallel with and a short distance from one edge and another similarly shaped and dimensioned ridge parallel with and a short distance from its other edge, the part of the plate outside of this latter ridge serving as 30 a nailing flange, a longitudinal pocket-like channel being formed inside of and adjacent to this latter ridge and opening toward the same and being less in height than the same, whereby the longitudinal edges of a series 35 of such plates may be overlapped and interlocked and the ridges of each pair of adjacent plates fit closely upon each other their entire length to form a reinforced upstanding ridge. Since the grant of this patent

40 this type of sheet metal roofing has been extensively manufactured and used and while it has proven of great practical and commercial value experience has shown that occasionally a high wind will work under 45 the roof and bulge upwardly the plates at points between the ridges and exerts such a powerful pull on the plates as to draw their edges out of the channels and thus free one edge of the plate. My present 50 improvement is designed to so construct the interlocking joint as to prevent this disconnection of the plates, the construction being such that when the plates are once interlocked and nailed down it will be practically impossible to dislodge or disconnect 55 them without first removing the nails in the

nailing flanges. This improvement will be best understood if it be kept in mind that this type of roofing plates is made in sizes very much larger than the well known 60 metal shingles on the market, this type of roofing plate being designed to take the place of these comparatively small shingles.

In the drawing *a* designates the main part of the plate, *b* the nailing flange 65 formed along one of the longitudinal edges of the plate, *c* the upstanding inverted V or U-shaped ridge formed adjacent to the nailing flange, *d* the second similarly shaped ridge extending along the plate near the 70 opposite edge thereof. To this extent the plate is constructed similarly to the plate in my former patent. At the junction of the inner wall *c'* of the ridge *c* and the main part of the plate, there is formed a longitudinal rib *e*, this rib being formed by folding the metal of the plate upon itself. This rib or flange extends the entire length of the sheet and projects away from the ridge, 75 it being inclined upwardly with respect to the upper face of the plate *a*, thus forming a pocket or channel *f* between it and the roofing plate. The other edge of the plate, that is, the edge of the plate beyond the ridge *d* is folded downwardly and backwardly upon itself to form a longitudinal 80 channel *g* which lies underneath the plate 85 and opens toward the adjacent ridge *d*.

It will be observed that when the edges of 90 the sheets thus constructed are overlapped and interlocked in the manner illustrated, the ridge *d* fits closely down upon the ridge *c* and thus reinforce each other, while the folded rib *e* fits into the channel *g* and thus locks the free edge of the sheet to the previously nailed plate. It will be observed 95 that by this interlocking arrangement it will be impossible to disconnect the plates by bulging them upwardly, so that high winds can have no effect upon the plates. It will be observed also that the proportions of the parts are such that when the edge of the sheet is started into the channel *f* the inner wall of the ridge *d* will just engage over 100 the apex of the ridge *c*, whereby when the upper plate is swung downwardly the inclination of the contacting walls of the ridges and the upward inclination of the longitudinal rib *e* will cause the plate to automatically seat itself in its locked position, 105 in which position the walls of the channel *g* closely hug the rib *e* and the walls of the 110

upper ridge *d* closely hug the under ridge *c*, thus making a firm and very rigid seam.

It will be observed that all the plates will be securely locked together and will form in 5 their entirety a structural unit and each plate will be required to be fastened at but one edge. A feature of importance lies in the fact that all the nails will be covered in the completed roof thereby avoiding leakage at the nail-holes. Also it will be observed that the seams are absolutely watertight at all points there being no uncovered raw edges at either side of the seams to permit water to flow or be blown up from any 15 direction over the seam ridge.

With the ordinary method of fastening metal plates to the roof-boards expansion and contraction soon loosens the nailed seams and thus inevitably causes leakage; I avoid 20 this objection by nailing my plates at one edge only, whereby the entire plate is left free to expand and contract. It will be observed also that my construction avoids the 25 objectionable wooden sticks heretofore used to support the ridges and receive the fastening nails, and it will be noted also that I avoid the use of all separate fastening clips.

The construction admits of the ridge being closed to form a more rigid upstanding 30 seam, these being perhaps desirable in some cases where a more rigid ridge is of advantage. This ridge may be closed up during the process of laying the roof, before the plate is nailed, by simply squeezing it with a 35 pair of ordinary tinners' tongs.

It will be observed that the upstanding ridges are practically the same height and

are both higher than the lock fold and that the lock fold opens away from the adjacent ridge. This construction causes the upstanding adjacent wall of the ridge to wedge or force the lock flange into the lock fold throughout its length so that the laying of the sheets will be an easy matter even with unskilled labor and the sheets will and in 45 fact must always be laid properly.

Having thus described my invention, what I claim as new and desire to secure by Letters Patent, is—

A sheet metal roofing plate having an upstanding ridge extending along near one of its longitudinal edges, a portion of the plate outside of this ridge being folded under to form a hook-like pocket opening toward the adjacent ridge, a second ridge similarly dimensioned and shaped being formed along the plate near its other longitudinal edge, the portion of the plate outside of this latter ridge forming a nailing flange, and a longitudinal rib *e* being formed at the junction 60 of the plate and the base of the last named ridge on the side opposite the nailing flange, this rib being formed by folding the plate and being extended in an inclined direction upwardly and away from the ridge so as to 65 form an inclined pocket or channel between itself and the face of the plate, said ridges being higher than the rib *e*.

In testimony whereof I hereunto affix my signature in the presence of two witnesses. 70

HENRY E. MOOMAW.
